HEATER

Lucius Foster Chase, Los Angeles, Calif.

Application January 27, 1933, Serial No. 653,783

6 Claims. (Cl. 126—59.5)

This invention relates to gas diffusing or deflecting appliances, and more particularly for outdoor use, as in heating orchards and the like.

Among the objects are, the provision of a device which will receive gases flowing from a conduit or stack in one direction and deflect same laterally, and more particularly, heated gases for warming out-of-door areas, which device will serve also as a cover or roof of the conduit, thereby shielding the latter and any associated device from rain or moisture; which device in deflecting and directing the gases avoids formation of eddies and vortices in changing the direction of flow of the hot gases so far as is reasonably and commercially possible; which device will not obstruct free flow of gases through and from a heating appliance to which the device may be attached and which device can be moved to extinguish fire in a heater to which the gas-conducting conduit leads, and which arrangement can be easily attached to the conduits or stacks of existing heating devices.

Other objects will appear as this description proceeds.

With the foregoing and other objects in view, the invention consists in the novel and useful formation, construction, interrelation and combination of parts, members and features, all as hereinafter described, shown in the drawing and finally pointed out in claims.

In the drawing:

Fig. 1 shows in perspective one form of this device in operating position.

Fig. 2 is a vertical elevation of the same device, partly in section, showing the relation of the parts when the device is moved to close the end of the stack and cut off the draft.

Fig. 3 is a plan and Fig. 4 is a sectional elevation of a variant of this device.

Fig. 5 is a plan and Fig. 6 is an elevation of another form of the device.

Fig. 7 is an elevation of another variant of the device, showing the heating unit having the stack or conduit attached thereto, drawn to a smaller scale.

In the illustrated examples shown, the heating unit itself is omitted except in the one case mentioned, namely Fig. 7. This heating unit may be of any preferred type and does not form a part of this invention.

The conduit or stack B provides draft for combustion and releases the hot gases at substantially the appropriate elevation for their discharge for heating whatever is to be warmed, as, for instance, the lower portions of orchard trees.

Obviously, the hot gases will rise vertically from the upper end 10 of the conduit, due both to their velocity of discharge and the tendency of hot gases to flow upward.

It is desired to spread the gases over the area of an orchard and thereby raise the temperature of the area to be warmed as uniformly as may be possible. Many devices have been tried to prevent rapid upward flow of the hot gases and to deflect them laterally and so spread them over a greater area at a more suitable height for warming the zone where heat is desired. The most of these possess certain defects which this invention is designed to correct.

The natural use of an umbrella or cone type of deflector is attended with the production of eddies or whirls, as is obvious from consideration of the conditions and the showing in certain of the drawings. The annular stream of hot gases near the center of the pipe will rise and strike the cone 20 deflector near its center so that the hot stream is turned laterally at that point to emerge in an approximately horizontal direction. The outer annular stream likewise rises to impinge against the deflector, and is turned horizontally outward. 25 Obviously the laterally moving gases from the portions of the deflector near the center will strike against the vertically moving gases which rise from the outer part of the stack whereby eddies and vortices are produced to such degree that the effectiveness of such deflector is very low and the purpose is not fulfilled except to a limited extent.

Other deflectors have certain objections which need not be here discussed.

As shown, this present invention comprises a series of deflectors grouped vertically. Considering Figs. 1 and 2, a conical deflector D—1 is mounted at the top, while below this top deflector is a frusto-conical deflector D—2, and below the second deflector is a third frusto-conical deflector D—3 and the number of successive deflectors may be as great as conditions may require. As shown in this particular example, all the deflectors are circular in plan and each has two parallel openings perpendicular to its axis except the topmost one, the lower opening being smaller than the upper opening. Lowermost deflector D—3 has its lower opening R—3, which is nearly as large in diameter as that of the conduit B, the body of the deflector being tapered outwardly so that the upper opening or base 14 is very slightly less in diameter than that of the conduit B. Deflector D—2 has a lowermost opening at 15, which is smaller than the opening 13 of deflector D—3, and like member D—3 is tapered 50

outwardly so that its maximum diameter at 16 is equal to that of the element D-3. Uppermost member D-1 is given approximately the same taper as that of the other two members described, but it has no central opening and its outer diameter is greater than that of the conduit B. These members are all fastened together, being spaced vertically apart and held centrally and coaxially over conduit B by means of ring C, which encircles conduit B, to which are fastened vertical support members E-1, E-2 and E-3, whereby the uppermost member D-1 is held in position. The two lower members, D-2 and D-3, are fastened to uppermost member D-1 by vertical parts F-1, F-2 and F-3. The dimensions are such that if uppermost member D-1 is pushed downward the deflectors D-2 and D-3, with their supporting members F, will pass down into the conduit, as shown in Fig. 2, while the top member D-1 rests against the upper edge 10 of the conduit B, thereby closing it and stopping the draft so that all combustion, in any heater to which conduit B leads, ceases. That is, by pushing down the deflecting assembly so that it takes the position shown in Fig. 2, the heat source is put out of commission without any further attention.

While the deflecting elements which are circular in plan may be at times the preferred form, there are conditions under which deflection, which is particularly directed and not uniformly around the conduit, may be preferred, as, for instance, the arrangement shown in Figs. 3 and 4. In the drawing is shown a deflecting arrangement which throws the hot gases in two opposite directions only, the deflectors being made of flat, inclined plates L-1, L-2, M-1, M-2 and N-1, N-2. As shown, the lowermost pair of plates are spaced with their opposing edges a considerable distance apart, while the next succeeding pair of plates have their edges brought closer together, the third or top pair of plates meeting and joining in the middle, transverse of the axis of the conduit B. In this case the parts are not intended to be moved, and when the draft is to be cut off for extinguishing the combustion in the heater or furnace, a cap J, having a handle K, is put over the upper end 10 of conduit B. The supports S-1 and S-2 are bent outwardly as shown to accommodate placing or removal of the cap K.

Figs. 5 and 6 show a three-directional deflecting means which is similar to the one just described except that the deflecting plates P-1, P-2, P-3, Q-1, Q-2, Q-3 and X-1, X-2, X-3 are arranged in triangular formation; that is, the plan is triangular as shown in Fig. 5. The supports for these plates, S, the supporting ring C, encircling stack or conduit B, and the expanded portions of the supports S to admit of an extinguishing cap such as is shown in Fig. 4 are all clear and obvious.

Fig. 7 shows three circular deflectors, D-1, D-2 and D-3, which are similar to those previously described and shown in Figs. 1 and 2, except that the supports S are bent outwardly just above the top end 10 of conduit B to receive extinguishing cap J. It will be seen from the drawing, and particularly from Figs. 2 and 4, that one principal feature of this invention is to avoid, or at least diminish, the eddy whirls which accompany the use of a single deflecting member. This is done by subdividing the column of hot gases into successive annular portions or segments, depending on the form of the deflector, and thereby diminishing the stream line crossings or interferences of the column of hot gases. For in-

stance, all of the gases rise through the top of the stack until the stream lines forming annule and indicated by the dotted lines a, b and c strike against the lower surface of deflector D-1. The innermost stream line c is deflected horizontally outwardly towards c-1 while the outermost stream line a strikes against the surface of the deflector D-3 and is turned outwardly in the direction a-1. Obviously the deflected stream line c-1 strikes the upwardly ascending stream 10 line a, while the outwardly deflected stream line b-1 also strikes against the vertically directed stream line a, it being obvious that any horizontally directed stream line must intersect the vertical stream line of any portion of the tube of hot gases lying at a greater radial distance from the center than does the vertical stream line which is so deflected. It is equally clear that the intersection of these stream lines cannot be prevented but it can be minimized by reducing the thickness 20 of the tube of hot gases or by breaking this tube up into successive portions, which is done in this invention. The entire gas tube rises vertically until the lowermost deflector D-3 is reached. Since this has a large aperture, only a small portion, forming an outer annulus of the hot gases, is arrested and deflected, the rest of the gases proceeding on upward until it strikes the next deflector, D-2, through which is also an aperture so that this second deflector cuts off and deflects 30 only a small portion of the total cross section of the hot gases rising from tube B, and the final area of the hot gases which reaches the top member D-1 has a diameter only as great as the aperture through the immediately preceding 35 member D-2. From this it is obvious that the total area of hot gases coming from the tube B is subdivided into comparatively thin laminae and these thin portions are successively deflected. While, of course, there will be whirls and vortices, due to the previously described intersections of vertical and horizontally-deflected stream lines, these will be greatly minimized and practically neutralized due to the subdivision and comparative smallness of the width of each of 45 the vertical stream areas deflected.

For convenience, these subdivisions of stream lines have been made in Figs. 2 and 4, the vertical ones being indicated by a to f, while the horizontal stream line corresponding to any vertical one is indicated by the same letter with the suffix "1".

Having described my invention in connection with illustrative embodiments, forms, proportions and arrangements of parts, it will be understood that many variants thereof are possible to those skilled in the art, and my invention, in its broader aspects, is not limited to the specific construction herein described and shown, as changes in the sizes, proportions, configurations arrangements, assemblage, interaction, juxtaposition and mechanical relations, as well as additions, omissions, substitutions, combinations and alterations of forms, parts, members and features may be made without departing from the broad spirit of this invention.

Having thus disclosed my invention, I claim and desire to secure by Letters Patent:

1. In a device of the nature disclosed, the combination of: a combustion heater for generating gas; a conduit for the gas extending from said heater; a plurality of members for deflecting said gas spatially mounted above the end of said conduit; and means connecting said deflecting members to move as a unit and supporting means for said unit, longitudinally slideable on the said con- 70

duit, there being a passage in each of said deflectors except the topmost one thereof, said conduit having a diameter sufficient to accommodate all of said deflectors and their connecting means except said topmost one whereby the entirety may be thrust into said conduit until said topmost deflector contacts with the end of said conduit and effects closure thereof.

2. In a device of the nature disclosed, the combination of: a combustion heater having a stack; means disposed adjacent the discharge end of said stack and functioning to divide the heated gases discharging therefrom into separate streams and to deflect said streams laterally, said means comprising a series of deflecting members disposed above the discharge end of said stack, all of said members, excepting the topmost one thereof, having axial openings progressively diminishing in area from the lowermost to the next to the topmost deflecting member; said members each providing deflecting surfaces angled relative to the axis of the stack so as to maintain the stream characteristic of the deflected gases and prevent turbulence thereof such as would appreciably affect the draft of said stack; means connecting said deflecting members in a vertical spatially separated group to move as a unit; and supporting means for said unit, adjustable axially of said stack, whereby said unit may be lowered to a position in which the topmost deflecting member will effect closure of the discharge end of the stack and another of said deflecting members will be disposed within said stack.

3. In a device of the nature disclosed, the combination of: a combustion heater having a stack; means disposed adjacent the discharge end of said stack and functioning to divide the heated gases discharging therefrom into separate streams and to deflect said streams laterally, said means comprising a deflecting member disposed over the end of said stack and covering a portion thereof and a second deflecting member above the first member and extending entirely over the end of said stack, said members each providing deflecting surfaces angled relative to the axis of the stack so as to maintain the stream characteristic of the deflected gases and prevent turbulence thereof such as would appreciably affect the draft of said stack;

means for connecting said deflecting members in relative spaced relationship to insure movement thereof as a unit, supporting means for said unit adjustable axially of the stack, said stack having a diameter sufficient to receive said first deflecting member whereby said first deflecting member may be thrust into said stack until the topmost deflecting member contacts the end of the stack and effects closure thereof.

5

4. In a device of the nature disclosed, the combination of: a combustion heater having a stack for the gases from said heater; a deflecting unit normally disposed adjacent the discharge end of said stack and comprising a plurality of deflecting members each whereof is formed and positioned to deflect some portion of the gases emerging from the stack outwardly therefrom and means for connecting said members in vertically spaced relationship; and means for slidably mounting said unit on said stack whereby said unit may be lowered to a position in which the topmost deflecting member will effect closure of the discharge end of said stack and another of said deflecting members will be disposed within said stack.

25

5. In a device of the nature disclosed, the combination of: a combustion heater having a stack for the gases from said heater; a deflecting unit normally disposed adjacent the discharge end of said stack and having an imperforate top member, said unit being formed and disposed to deflect said gases laterally in successive portions, while the undeflected portion continues to follow the main stream direction; and means for slidably supporting said unit on said stack, 30 whereby said unit may be lowered to a position in which said imperforate top member will effect closure of the discharge end of said stack to extinguish the fire in the heater.

35

6. An orchard heater having a stack, a deflecting unit supported above the discharge end of the stack and comprising a plurality of deflecting members and means for connecting said members in vertical spaced relationship, said deflecting members being constructed to deflect the 40 discharged gases laterally while maintaining the stream characteristic of the discharged gases, and means to effect a closure of the discharge 45 end of the stack.

LUCIUS F. CHASE. 50
